William F. Steers, Short Hills, N. J., assignor to Glaser-
Steers Corporation, Belleville, N. J., a corporation of
New Jersey

Application September 20, 1955, Serial No. 38,008

Term of patent 14 years

(Cl. D26—14)

Fig. 1 is a top plan view of a phonograph pick-up arm, showing my new design;

Fig. 2 is a side elevational view thereof;

Fig. 3 is a front end elevational view thereof, looking at the left end in Fig. 2;

Fig. 4 is a rear end elevational view thereof, looking at the right end in Fig. 2;

Fig. 5 is a front perspective view thereof; and

Fig. 6 is a rear perspective view thereof.

The dominant features of my new design are shown in solid lines in the drawing, the broken line showing the

pivot post being omitted from Figs. 4 and 5 for convenience in illustration.

I claim:

The ornamental design for a phonograph pick-up arm, as shown and described.
